UNITED STATES PATENT OFFICE.

FRED S. HEATH, OF EPSOM, NEW HAMPSHIRE.

FOUNTAIN-PEN.

SPECIFICATION forming part of Letters Patent No. 423,684, dated March 18, 1890.

Application filed March 23, 1889. Serial No. 305,612. (No model.)

To all whom it may concern:

Be it known that I, FRED S. HEATH, a citizen of the United States, residing at Epsom, in the county of Merrimac and State of New Hampshire, have invented certain new and useful Improvements in Fountain-Pens, of which the following is a specification.

The object of my invention is to provide a fountain-pen with a flexible tip capable of taking the place of an ordinary pen, which must be attached thereto.

The invention will be clearly understood by reference to the accompanying drawings, forming a part of the following specification and claims, of which—

Figure 1 is a broken elevation showing the top side of the pen. Fig. 2 is a similar elevation showing the pen in side view. Fig. 3 is a longitudinal sectional view showing the interior arrangement of my improved pen-point. Fig. 4 is a view of the open end of the pen-point detached from the reservoir or barrel.

Similar letters indicate like parts.

25 My improved pen-point A, I form conical for about two-thirds its length, more or less, the balance being cylindrical, and in the conical portion are formed the slots B B, located at opposite sides, which divides the 30 top part *a* from the bottom part *a'*, and in the top part *a* is formed a slot B'. These several slots, in connection with a valve C, to be hereinafter explained, serve the ink to the paper when the pen is in use. The 35 slotted portion *a* of the pen-point A is preferably made slightly longer than is the portion *a'*, for a purpose also to be hereinafter set forth.

The valve C is made tapering to correspond with the interior of the parts *a* *a'*, forming the writing-tip of the pen-point A, and it may be located at a point to cover the upper end of the slots B B', or at a point below their upper ends as desired; and it may 45 be formed integral with or be mounted upon

a stem *c*, which is threaded to a threaded opening in a disk D, having perforations *d* for the passage of ink from the handle or ink-reservoir E, to which the pen-point A may be threaded in the usual way, as at *e*, Fig. 3. 50 The disk D is turned a snug fit for that part of the pen-point in which it is placed, and it may rest upon a shoulder *a*², as seen in Fig. 3. When the said point A is removed from the handle E, the disk and valve, by means 55 of the valve-stem *c*, may be easily withdrawn for the purpose of cleaning the parts.

To prepare the pen for use, the valve-stem *c* is rotated in the disk D until the valve C is adjusted to closely fit the interior of the 60 parts *a* *a'* of the pen-point A without spreading open the slots B B'. Then the pen-point may be placed upon the ink-reservoir or handle E, when the improved pen is ready 65 for use.

By the action of the extending points of the part *a* upon the paper, thus spreading the slots B, ink is allowed to pass the valve C, and by varying the pressure of the pen upon the paper the slot B' is accordingly spread 70 open, and a coarse or fine line is the result.

Having described my improvements, what I claim, and desire to secure by Letters Patent, is—

1. In a fountain-pen, a pen-point formed 75 conical and having slots, as shown, and provided interiorly with an adjustable valve, substantially as and for the purpose set forth.

2. In a fountain-pen, a conical pen-point slotted as shown, and having its upper part 80 slightly longer than its lower part, and an adjustable valve fitting the interior of said slotted portion, substantially as and for the purpose specified.

In testimony whereof I affix my signature in 85 presence of two witnesses.

FRED S. HEATH.
